UNITED STATES PATENT OFFICE.

JACKSON B. MILES, OF LINCOLNTON, GEORGIA, ASSIGNOR OF TWO-THIRDS
TO W. H. GROVES AND C. S. HOLLINSHEAD, BOTH OF SAME PLACE.

LOGGERHEAD FOR HAMES.

SPECIFICATION forming part of Letters Patent No. 416,684, dated December 3, 1889.

Application filed June 29, 1889. Serial No. 316,013. (No model.)

To all whom it may concern:

Be it known that I, JACKSON B. MILES, a citizen of the United States, and a resident of Lincolnton, in the county of Lincoln and State of Georgia, have invented certain new and useful Improvements in Loggerheads for Hames; and I do declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 Figure 1 of the drawings is a representation of this invention and is a perspective view. Figs. 2, 3, and 4 are perspective views of the different portions of the loggerhead.

This invention relates to loggerheads or 20 tug-hooks for hames; and it consists in the novel construction and combination of parts, as hereinafter described, and pointed out in the claim.

In the accompanying drawings, the letter 25 A designates the harness-hame, and B the detachable loggerhead or tug attached thereto by the staple V.

The loggerhead or tug is recessed or cut out at a, on both upper and lower edges, to form 30 double hooks b for the attachment of the chain or trace c. The forward portion of the tug is reversely curved, as at d, to form a broad bearing-hook e, to engage the staple V

of the hame, and the said tug is retained on the staple by the angular keeper-plate D, 35 which is secured to the tug by the screw h.

The object of the invention is to provide a simple and effective tug-hook which may be applied to the staple of the hame without withdrawing the latter in case of accident to 40 the tug.

In attaching the tug to the staple on the hame it is necessary to remove the shield or keeper plate. The hook portion d of the tug is then slipped around the hame-staple and 45 the keeper-plate fastened in position, effectually securing the tug to the hame. The tug being provided with two hooks is thereby made doubly effective, for should one hook break or be otherwise injured the draft-chain 50 is ready to be geared to the other hook.

Having described this invention, what I claim, and desire to secure by Letters Patent, is—

The detachable tug - fastening for hames, 55 comprising the tug having a hook d at its forward end and the angular keeper-plate D, connected to the tug and engaging the beak of the hook d, substantially as set forth.

In testimony whereof I affix my signature in 60 presence of two witnesses.

JACKSON B. MILES.
